UNITED STATES PATENT OFFICE.

EUGÈNE SCHNEIDER, OF LE CREUZOT, FRANCE.

GUIN-MOUNTING.

1,166,086.

Specification of Letters Patent. Patented Dec. 28, 1915.

Application filed January 20, 1915. Serial No. 3,318.

To all whom it may concern:

Be it known that I, EUGÈNE SCHNEIDER, a citizen of the Republic of France, residing at Le Creuzot, Saône-et-Loire, France, have invented a new and useful Improvement in or Relating to Gun-Mountings, which is fully set forth in the following specification.

This invention relates to gun mountings of the kind in which roller or ball bearings are employed upon which the carriage moves during training. In gun mountings of this type it is desirable to relieve the roller or ball bearings from the recoil strains. With this object it has been proposed to interpose between the outer bearing ring of each roller bearing and the mounting or the carriage an annular spring the compression of which during firing absorbs the recoil strains transmitted by the brake. This known arrangement has the disadvantages of necessitating annular springs and of speedily becoming inoperative. The annular springs become deformed under the influence of the radial strains whose directions vary in accordance with the firing direction and there are no available means for correcting the effects of local deformation, so that the centering of the pivot speedily becomes defective. This defective centering immediately gives rise to friction in places in which the ball bearing or bearings should eliminate such friction. Moreover the annular springs are difficult of access and their condition may become highly defective without any outward indication of the fact, the result being that in the course of firing a spring may break without the slightest warning.

According to the invention the ball or roller bearings are provided with a shock absorber which is displaceable with the gun carriage and arranged in the direction of firing which position it always occupies at all angles of training. The device in question consists of a metal or other spring arranged between the carriage and a shoulder formed upon the outer end of a radial extension of the supporting ring of the ball or roller bearing, the said extension being arranged in the plane of the vertical axis of the gun.

In order that the said invention may be clearly understood and readily carried into effect, I will describe the same more fully

with reference to the accompanying drawings, in which:

Figure 1 is a sectional elevation on the line I—I of Fig. 2 illustrating the application of the invention to a gun carriage mounted on a platform and displaceable about a fixed pivot between which and the carriage a ring of rollers is arranged. Fig. 2 is a sectional plan on the line II—II of Fig. 1. Figs. 3 to 6 illustrate the invention applied to a pedestal mounting, and in these figures. Fig. 3 is a sectional elevation on the line III—III in Fig. 4, which is a sectional plan on the line IV—IV of Fig. 3. Figs. 5 and 6 are partial sections on the lines V—V and VI—VI respectively of Fig. 3.

Referring to Figs. 1 and 2, A is the carriage which carries a turntable a mounted upon frusto-conical rollers C bearing upon a base plate B provided with a double pivot b b'. Between the pivot b' and a bearing ring D rollers E are interposed. The means for relieving these rollers from the firing strains is constituted in the following manner: The ring D comprises a radial extension d passing through a bearing a' on the carriage A or its turntable a and arranged in the plane of the vertical axis of the gun. At the outer extremity of this extension d an adjustable collar d' is arranged and a spring F is disposed between this collar and the outer face of the bearing a'. During firing, the gun carriage A is displaced by the gun and at once bears upon the pivot b by means of the socket a² and compresses the spring F by means of the bearing a'. Between the shoulder D' of the ring D and the bearing a', a clearance exists equal to the clearance that existed between a² and b. After firing, the spring F brings the gun carriage A back against the shoulder D'. It will be noted that the roller bearing is relieved from the firing strains and that the shock absorbing springs, which are visible and readily accessible, experience only axial strains that is to say strains in the direction of their flexibility; in other words, they do not experience any abnormal deformation.

Referring to Figs. 3 to 6 the lower face of the carriage A carries a pivot A' movable in an upper collar B' of a pedestal B and bearing by means of its lower extremity upon a bearing ring B². The pivot A' is guided upon a vertical trunnion b' rigid with the pedestal. Between the trunnion b' and the

105

110

socket a^2 of the pivot A' and between a projection a' formed beneath the carriage A and the collar B', roller bearings are arranged which (as in the preceding example) 5 comprise a ring D provided with an extension d engaging in a bearing formed upon the gun carriage and arranged in the plane of the vertical axis of the gun. The lower shock absorbing device is directed oppositely 10 to the upper shock absorbing device. During firing, the pivot A' bears upon the collar B' and upon the trunnion b' by means of a collar A²; the clearance normally existing between the rear of the pivot A' and the collar B' disappears and a corresponding clearance occurs between the projection a' and the shoulder D' of the upper ring D. The 15 normal clearance between the parts b' and A² disappears and a corresponding clearance 20 occurs between the shoulder D' of the lower ring and a².

What I claim and desire to secure by Letters Patent of the United States is:—

1. In combination, a revoluble gun-supporting frame, a base having a pivot for carrying said frame, anti-friction means between said pivot and said frame, and adjustable shock-absorbing means for relieving said anti-friction means from firing strains. 25
2. In combination, a revoluble gun-supporting frame, a base having a pivot for carrying said frame, anti-friction bearing means between said pivot and said frame, and adjustable shock-absorbing means external of 30 the frame for relieving said bearing means from firing strains.
3. In combination, a revoluble gun-supporting frame, a base having a pivot for carrying said frame, anti-friction means between said pivot and said frame, and an adjustable yielding means engaging said frame and said anti-friction means for relieving said anti-friction means from firing strains. 40
4. In combination, a revoluble gun-supporting frame, a base having a pivot for carrying said frame, anti-friction bearing means between said pivot and said frame, a spring normally resisting movement of 45 said frame and reacting through said bearing means on said base, and means for adjusting the tension of said spring.
5. In combination, a revolably supported gun-carriage frame, an upright shouldered 50 pivot member about which said frame rotates, roller bearing means between said frame and said pivot, adjustable yielding means engaging said frame and said bearing 55

means, and a collar on said frame for receiving the shoulder of said pivot. 60

6. In combination, a revoluble gun-supporting frame, a base having a pivot, anti-friction bearing means surrounding said pivot, a ring member surrounding said bearing means and having a projecting lug which 65 extends through a portion of said frame, and shock-absorbing means held between the end of said lug and said frame.

7. In combination, a revoluble gun-supporting frame, a base having a pivot, anti-friction bearing means engaging said pivot, an annular ring surrounding said bearing means and having a projection extending through a portion of said frame, adjustable shock-absorbing means associated with said 75 projection and said frame, and other bearing means for maintaining said frame in alignment with said base.

8. In combination, a revoluble gun-supporting frame, a base member for supporting said frame, antifriction bearing means operating against external parts of said base, annular means for retaining said bearing means in position, a projection on said annular means passing through a portion of 85 said frame and receiving a shock-absorbing means, and other bearing means for maintaining other portions of the frame in normal position. 90

9. In combination, a revoluble gun-supporting frame, a base member having a pivot, antifriction bearing means engaging said pivot, annular means between said bearing means and said frame, a projection on said annular means extending through a portion 95 of said frame, and adjustable shock-absorbing means associated with said projection and said frame, said absorbing means being accessible from outside said frame and said base. 100

10. In combination, a revoluble gun-supporting frame, a base member for supporting said frame, anti-friction bearing means operating against external parts of said base, annular means for retaining said bearing means in position, and a projection on said annular means passing through a portion of said frame and receiving a shock-absorbing means. 105

In testimony whereof I have signed this 110 specification in the presence of two subscribing witnesses.

EUGÈNE SCHNEIDER.
